CLOSURE FOR A COSMETIC CONTAINER

William H. Harris, Litchfield, Conn., assignor to Scovill Manufacturing Company, Waterbury, Conn., a corporation of Connecticut

Filed Nov. 23, 1959, Ser. No. 58,431

Term of patent 7 years

(Cl. D58—26)

Fig. 2

Fig. 1 is a top plan view of a closure for a cosmetic container such as used on cosmetic containers, showing my new design; and

Fig. 2 is a side view of the same.

The essential features of my design reside in the portions shown in full lines.

I claim:

The ornamental design for a closure for a cosmetic container, as shown and described.
